UNITED STATES PATENT OFFICE.

WILLIAM G. CHAPIN, OF BROOKLYN, NEW YORK, ASSIGNOR TO THE THOMPSON & NORRIS COMPANY, OF SAME PLACE.

METHOD OF PACKING GOODS.

SPECIFICATION forming part of Letters Patent No. 484,628, dated October 18, 1892.

Application filed October 31, 1891. Serial No. 410,533. (No model.)

To all whom it may concern:

Be it known that I, WILLIAM G. CHAPIN, of Brooklyn, Kings county, and State of New York, have invented a certain new and useful 5 Improvement in Methods of Packing Goods, of which the following is a specification.

The object of the present improvement is to afford greater facility for making packages of small articles of merchandise. The material 10 which I contemplate using is composed of a corrugated strip of paper or like substance united, preferably, with a plain strip of similar substance.

My improvement consists in taking a strip 15 of packing material of the character described, bending or folding it suitably to partially form the body of a box, introducing the article or articles to be packed within it while in this condition, bending or folding the material still further to complete the body of the 20 box, and inserting at any suitable time in the process of making the body of the box cross - pieces, and, if necessary, cross-pieces intermediate of the first-named cross-pieces.

25 Preferably the packing material will be preliminarily creased by a machine or otherwise, so as to facilitate the bending or folding of it in the required manner. It will be advantageous to place the packing material after 30 being partially bent in a holder to retain it in position while articles are placed within it and its cross-pieces are inserted in their places.

In the accompanying drawings, Figure 1 is a perspective view of a piece of packing material partly bent or folded to form the body of a box, some articles introduced therein, and a holder for retaining the partly-completed package. Fig. 2 is a perspective view of a completed box with one of the cross- 40 pieces partly removed.

Similar letters and numerals of reference designate corresponding parts in both figures.

A designates a strip of packing material consisting of a corrugated strip a' of paper 45 or like substance and a plain strip a'' of like substance, attached to one side thereof by paste or other adhesive substance.

I have shown the strip A of packing material as rolled up. The roll may be supported 50 upon a shaft, so that it can be readily drawn off.

I have shown the strip of packing material A as longitudinally creased, so that it may be readily bent or folded transversely. It is represented as having four of such longitudinal creases 1 2 3 4. 55

B designates a holder, here shown as consisting of a base-piece b, having uprights or posts b' , fixed near one edge, and uprights or posts b'' , adjustably connected with the base-piece b. As here shown, the base-piece b is provided with dovetailed grooves b^3 , and the lower extremities of the uprights or posts b'' are fitted to slide along these grooves toward and from the uprights or posts b' . The lower 60 extremities of the posts are intended to be made in the form of dovetailed tongues or tenons fitting the grooves b^3 and are combined with loose plates b^4 , which are laid across the tops of the grooves and are forked to embrace the uprights or posts b'' . These plates can slide up and down the uprights or posts b'' . Screws b^5 , passing through the plates b^4 and engaging with holes in the lower extremities of the uprights or posts b'' , fitting in the 65 grooves b^3 , serve to clamp the plates b^4 down upon the top of the base-piece b and draw up the dovetailed lower extremities of the uprights or posts b'' against the overhanging walls of the grooves b^3 . To enable the screws to do 70 this, it is of course necessary to provide them with shoulders bearing upon the tops of the plates b^4 . Obviously the holder B may be adjusted to different-sized packages. Where the 75 packing material is creased in the manner described, it will be advantageous only for a certain-sized box, and the holder will not need adjusting so long as a strip of packing material which is uniform in its size and the position of its creases is used; but the adjustability of the holder is advantageous, because 80 it enables strips of packing material A of different proportions to be used for making different-sized boxes. Of course the holder will 85 not require adjustment to suit packages of various lengths, but only for packages varying 90 in transverse section.

To make a package in accordance with my improvement, it is only necessary to cut from the strip of packing material A a piece A', of a size suitable for the desired length of package, and treat it as I will now explain. The 95 100

cut piece A' will be bent or folded along its crease 4, and again along the line of its crease 3, so as to bring it to the form of a trough. Then it may be slipped into the holder B, between the uprights or posts b' and the uprights or posts b². Cross-pieces A² may then be fitted to the trough-like portion—as, for instance, by slipping them in the grooves formed by the outwardly-extending corrugations. The articles to be packed may then be slipped into the trough-like portion of the package, and where they are of less length than the length of the body of the package formed of the piece A' it will be advantageous to introduce intermediate cross-pieces A³. These may be slipped into the corrugations of the piece A'. After the packing has thus been completed the piece A' will be folded along its crease 2 and then along its crease 1, and the edge beyond the latter slipped over the other edge of the piece A, so as to form a lap. The package may then be removed and fastened in any suitable manner—as, for instance, by tying a string around it or applying a wrapper of paper and pasting the edges, or by simply slipping a rubber band or bands over it. Obviously the inner sides of the uprights or posts b² may be cut away, as indicated by the dotted line b³, so that the said uprights or posts will contact with the lower part of the adjacent side of the piece A' of packing material, but yet will allow the edge which is last folded over to be slipped down in front of them.

35. The cross-pieces may severally consist of a piece of corrugated paper or like substance faced on each side with a piece of plain substance of like character fastened to it by means of paste or other adhesive substance, 40 but I am unwilling to be limited to any particular construction.

45. By my improvement I produce a very desirable package for small articles of merchandise, which can be readily made. When completed, it will be very strong, although light and cheap. It will be so elastic as to afford great protection to the articles contained in it, and its intermediate cross-pieces will keep different articles apart and protect them from 50 contact with each other. Obviously the cross-pieces may be made narrower than the depth of the body of the package, so as to allow of articles passing between them and an opposite wall of the body of the package. It is also apparent that the cross-pieces may be notched or perforated to accommodate articles.

55. My improvement affords great advantages over ready-made packages of the same material as that which I use, because it affords op-

portunity for making packages to suit different-sized articles as the same may be vended and to make up the packages to the best advantage for the protection of such articles.

What I claim as my invention, and desire to secure by Letters Patent, is—

1. The method of packing articles of merchandise, consisting in taking a strip of elastic packing material, bending or folding it suitably to partially form the body of a box, introducing the article to be packed within it, bending or folding the material still further to complete the body of the box, and inserting cross-pieces during the process of making the body of the box, substantially as specified.

2. The method of packing articles of merchandise, consisting in taking a strip of elastic packing material, bending or folding it suitably to partially form the body of a box, introducing the article or articles to be packed within it, bending or folding the material still further to complete the body of the box, and inserting in the process of making the body of the box cross-pieces and cross-pieces intermediate of the first-named cross-pieces, substantially as specified.

3. The method of packing articles of merchandise, consisting in taking a strip of elastic packing material, bending or folding it suitably to partially form the body of a box, fitting it in a holder while thus bent or folded, introducing the article or articles to be packed within it while it remains in the holder, bending or folding the material still further to complete the body of the box, and inserting, in the process of making the body of the box, cross-pieces, and cross-pieces intermediate of the first-named cross-pieces, substantially as specified.

4. The method of packing articles of merchandise, consisting in taking a strip of corrugated packing material, bending or folding it suitably to partially form the body of a box, fitting it in a holder while thus bent or folded, introducing the article or articles to be packed while it remains in the holder, bending or folding the material still further to complete the body of the box, and in the process of making the body of the box inserting cross-pieces into the corrugations of the material forming the body of the box, substantially as specified.

In testimony whereof I have signed my name to this specification in the presence of two subscribing witnesses.

WILLIAM G. CHAPIN.
